His attorneys.

UNITED STATES PATENT OFFICE.

REUBEN HENRY ANDREWS, OF WASHINGTON, DISTRICT OF COLUMBIA.

WOOD-WORKING MACHINE.

SPECIFICATION forming part of Letters Patent No. 299,190, dated May 27, 1884.

Application filed October 2, 1883. (No model.)

To all whom it may concern:

Be it known that I, REUBEN H. ANDREWS, a citizen of the United States, residing at Washington, in the District of Columbia, have 5 invented certain new and useful Improvements in Wood-Working Machines, of which the following is a specification, reference being had therein to the accompanying drawings.

10 This invention relates to wood-working machines, and is specially intended to be applied to a machine of the character shown in my Patent No. 250,181, of November 29, 1881, which I call my "complete wood-working machine."

15 The object of the present invention is to improve the driving mechanism for the shaping or friezing tool of such a machine as is above indicated.

20 The particular details of construction which constitute my present invention will be hereinafter pointed out in the claims.

In the drawings, Figure 1 is a plan, partly in section, showing such parts of the driving mechanism as constitute my present improvement, the table of the machine being removed. Fig. 2 is an end view of the machine, showing only such parts of the machine as illustrate my present invention. Fig. 3 is a side 25 view of the shipper-lever and a section of the bevel-pulley mounted thereon. Fig. 4 is a plan view of bell-crank lever. Fig. 5 is a detail showing the arm which carries idler-pulley *i*.

30 A represents the frame of the machine; G, the shaping-cutter mounted on rotating shaft G', as in my patent referred to.

a is a driving-shaft, provided with two bevel friction-pulleys, *b c*, as shown.

35 A bevel friction-pulley, *d*, is journaled on a standard, *d'*, which is carried by a shipper-lever, *e*. This lever is pivoted at *e'* to a cross-bar, *A'*, of the frame. The end *e''* of the lever *e* is pivoted to an arm, *f'*, of bell-crank lever *f*, which is provided with a slot, *f''*, for the 40 reception of the projection *e''* of lever *e*. The bell-crank lever *f* is pivoted at *x* to a cross-bar, *A''*, of the frame. Thus the movement of bell-crank lever *f* from the position shown in full lines to the position shown in dotted 45 lines in Fig. 1 will throw the pulley *d* out of contact with pulley *b*, and if the lever is moved far enough said pulley *d* will be thrown into contact with pulley *c* and driven in reverse direction, or in intermediate position 50 between *b* and *c* the pulley *d* will be at rest.

The belt *g* leads from pulley *d* around the guide or idler pulleys *h i* to the pulley *g'*, so as to drive said pulley and its shaft and shaping-cutter. The relation of pulley *d* to the guide-pulleys or idlers *h i* is such that the 55 tension of the belt *g* will be substantially the same, whichever one of pulleys *b c* may be engaged by said pulley *d*. The idler-pulley *i*, which serves to tighten belt *g*, is carried on a spindle, *i'*, on arm *K*. Said arm *K* has a 60 sleeve which embraces the stationary shaft *h'*, and is secured thereto by set-screw. Thus the arm *K* may be swung on shaft *h'* in the direction of the arrow, and the belt thereby be tightened.

65 The bevel friction-pulleys *b c d* may be faced with wood, leather, or other suitable material.

70 The end of bell-crank lever *f* is so located as to be within convenient reach of the foot of the operator.

75 The cutter *G* is of the kind adapted to cut whichever direction its shaft is driven.

I claim—

1. The combination, with a shaping-cutter and the driving-belt thereof, of bevel friction-pulleys, as *b c*, a bevel friction-pulley arranged, as described, between the two, so as to be brought in contact with either, a shipper-lever which carries said intermediate bevel-pulley, and a lever for operating said shipper-lever, substantially as described. 80

2. The bell-crank lever pivoted to the frame and to the shipper-lever, as shown, the shipper-lever carrying the friction driving-pulley, as described, the friction-pulleys arranged to 85 be engaged by said driving-pulley, the guide-pulleys arranged as shown, the belt, and the cutter-carrying shaft and pulley, all arranged and combined in a wood-working machine of the character described, as and for the purposes set forth. 95

3. The combination, with the cutter driving-pulley, of the friction driving-pulley and its shifting mechanism, substantially as described, the idler *h*, mounted on shaft *h'*, and the idler *i*, mounted on a spindle on arm *K*, said arm being adjustably secured to shaft *h'*, substantially as shown and set forth. 100

In testimony whereof I affix my signature in presence of two witnesses.

REUBEN HENRY ANDREWS.

Witnesses:
